UNITED STATES PATENT OFFICE.

CARL G. GROSS, OF MOUNT VERNON, NEW YORK, ASSIGNOR TO HALLIWELL-SHELTON ELECTRIC CORPORATION, OF NEW YORK, N. Y., A CORPORATION OF NEW YORK.

DESIGN FOR A CASING FOR AN EXERCISING MACHINE.

Application filed December 28, 1928. Serial No. 29,428. Term of patent 7 years.

To all whom it may concern:

Be it known that I, CARL G. GROSS, a citizen of the United States, residing at Mount Vernon, in the county of Westchester and State of New York, have invented a new, original, and ornamental Design for a Casing for an Exercising Machine, of which the following is a specification, reference being had to the accompanying drawing, forming part thereof.

The figure is a perspective view of a casing for an exercising machine showing my new design.

I claim:

The ornamental design for a casing for an exercising machine, as shown.

CARL G. GROSS.
